UNITED STATES PATENT OFFICE.

JOHN M. S. ANDERSON, OF BRIDGEPORT, CONNECTICUT, ASSIGNEE TO THE PERKINS ELECTRIC SWITCH MANUFACTURING COMPANY, OF BRIDGEPORT, CONNECTICUT, A CORPORATION OF CONNECTICUT.

PUSH-BUTTON SWITCH.

1,176,635.

Specification of Letters Patent. Patented Mar. 21, 1916.

Application filed July 20, 1915. Serial No. 40,878.

To all whom it may concern:

Be it known that I, JOHN M. S. ANDERSON, a citizen of the United States of America, and residing at Bridgeport, in the county of Fairfield and State of Connecticut, have invented certain new and useful Improvements in Push-Button Switches, of which the following is a specification.

My invention relates to electric switches of the push-button type, and more particularly to such switches of that type as have the rocking parts of the switch mechanism mounted in metal frames secured to the porcelain casing.

The object of my invention is to provide means whereby such metal frames may be securely held from being worked loose in the porcelain by the snap action of the mechanism when the switch is actuated.

In the accompanying drawing, I have shown my invention as applied, by way of illustration, to the push button switch for which Carl Eric Anderson applied for a patent May 8, 1915, Serial No. 26,782, but it will be understood that my invention may be employed in other constructions.

In this drawing, Figure 1 is a transverse section of the switch on the line 1—1, Fig. 2; Fig. 2 is a face view, with the face plate and insulating sheet removed; Fig. 3 is a section on the line 3—3, Fig. 2; and Fig. 4 is a perspective view of the metal frame on which the moving parts of the switch are mounted.

The cup-shaped casing A of porcelain or other insulating material may have at the corners (three in the illustration) binding posts 10, 10, near the surface for the binding wires, and secured to them suitable spring contact clips 11. To act in conjunction with these there is a swinging contact yoke 12, pivoted at 13 in the sides of a yoke-shaped frame 14. This frame has on its opposite sides feet 15 fitting in seats 16 at the bottom of grooves 17 in the inner faces of the opposite side walls of the insulating casing A. The frame 14 is secured in place by

screws 18 inserted from the back through holes in the porcelain and screwed into threaded holes in the feet 15, Figs. 1, 2 and 4. In this frame is also mounted the cross pin 19, on which the rocking lever 20 is pivoted to the frame, and to the outer ends of this rocking lever are pivoted the stems of the respective push buttons 21 in any suitable way. A central arm 22 on the rocking lever 20 acts upon a pin 23, guided in the yoke and surrounded by a coiled spring 24, so that on pushing down the right hand push button 21, Fig. 3, for instance, the arm 22 will compress the spring 24 with a toggle action, until the point of connection of this arm 22 passes the center line, whereupon the reaction of the spring 24 will throw the contact yoke 12 over from the position shown in Fig. 3 to a position where it contacts with the clips 11 at the right hand side in that figure. But as I have intimated, the details of the switch mechanism form no part of my present invention.

My invention relates essentially to the provision of means whereby the frame 14 may be held securely against tendency to work the securing screws 18 loose by the rocking and snap action of the moving parts of the switch. For this purpose, I fixedly attach to the outer part or arch of the frame 14, as by riveting or other means, a cross bar 25, whose opposite ends enter and snugly fit into the grooves 17 in the side wall of the insulating case and bearing against the walls of said grooves, at a distance from the screws 18, will effectually counteract any tendency of the frame 14 from rocking upon its feet 15 as the switch mechanism is snapped back and forth.

I claim as my invention:

1. A push button switch, having an insulating casing with rocking switch mechanism, a fixed frame in which said mechanism is mounted and can move, screws for securing the frame in the casing and a cross-bar on said frame at a distance from said securing screws and engaging the casing.

2. A push button switch, having a yoke-shaped frame with feet, switch mechanism mounted in the frame, an insulating casing having side grooves and seats for the feet of
5 the frame and a cross bar on the frame engaging the walls of said grooves, for the purpose described.

In testimony whereof I have signed my name to this specification, in the presence of two subscribing witnesses.

JOHN M. S. ANDERSON.
